Attorney

UNITED STATES PATENT OFFICE.

PAUL KRONE, OF CHICAGO, ILLINOIS.

DESIGN FOR AN AUTOMOBILE RADIATOR-CAP ORNAMENT.

Application filed March 5, 1929. Serial No. 30,325. Term of patent 7 years.

To all whom it may concern:

Be it known that I, PAUL KRONE, a citizen of the United States, residing at 6641 Greenview Avenue, in the city of Chicago, county of Cook, and State of Illinois, have invented a new, original, and ornamental Design for an Automobile Radiator-Cap Ornament, of which the following is a specification, reference being had to the accompanying drawing, forming part thereof:

Figure 1, is a side elevation of an automobile radiator cap ornament showing my new design, and Figure 2, is a front view of same.

I claim:

The ornamental design for an automobile radiator cap ornament as shown.

PAUL KRONE.
